UNITED STATES PATENT OFFICE.

OTTO PETERMANN, OF NEW YORK, N. Y., ASSIGNOR, BY MESNE ASSIGNMENTS, TO
STANDARD TYPEWRITER COMPANY, A CORPORATION OF NEW YORK.

TYPE-WRITING MACHINE.

1,089,345.

Specification of Letters Patent.

Patented Mar. 3, 1914.

Application filed June 12, 1909. Serial No. 501,852.

To all whom it may concern:

Be it known that I, OTTO PETERMANN, a citizen of the Republic of Switzerland, and a resident of New York, county and State of 5 New York, have invented certain new and useful Improvements in Type-Writing Machines, of which the following is a full, clear, and exact description.

This invention relates more particularly 10 to the line-lock mechanism of a foldable front strike or visible type-writing machine.

The primary object of the invention is to provide simple and efficient means serving as a line lock to adapt the machine to stop

15 the carriage at a certain point in its movement across its support, and to permit the carriage to be quickly released for the purpose of adding an additional character or characters at the end of a line and then

20 again lock the carriage against further movement as is often required to divide properly a word at the end of a line and at the same time to prevent the carriage from moving too far when the keys are operated.

25 A further object of the invention is to provide a machine in which the platen, carriage and line-lock mechanism may be moved vertically to different distances to adapt the type-heads to have a plurality of 30 characters thereon, and the carriage support and mechanism mounted thereon folded over above the keyboard so that the machine will occupy less space than when in use in case it is desired to transport the machine or 35 for other purposes.

With these and other objects in view, the invention will be hereinafter more particularly described with reference to the accompanying drawings, which form a part of 40 this specification, and will then be pointed out in the claims at the end of the description.

In the drawings, Figure 1 is a fragmentary vertical section, partly in elevation, of 45 one form of machine embodying my invention. Fig. 2 is a fragmentary rear elevation. Fig. 3 is a detail perspective view of a device forming a part of the line-lock mechanism. Fig. 4 is a fragmentary sectional inverted plan showing in elevation the line-lock lever. Fig. 5 is an inverted plan view of the carriage support removed from the machine; and Fig. 6 is a fragmentary side elevation of the upper part of the machine. 55

The machine hereinafter set forth is of the type shown in the patent to Frank S. Rose, No. 754,242, patented March 8th, 1904, in which the carriage is adapted to be folded over above the keys, and while in the present invention the carriage and platen and their operating mechanisms are adapted to be raised and lowered on the frame of the machine and to be folded over above the finger keys, and in which the type-bars have a 60 front strike for visible writing, it is to be understood that the features of this invention may be used in connection with other classes of machines.

The metallic frame 25 Figs. 1 and 2, of 70 the machine is constructed and arranged in any suitable manner, and may consist of side members and an integral back member with an intermediate transverse horizontal bar 26 suitably fastened to the sides of the frame 75 and serving as a brace therefor, the whole frame being constructed of sheet metal with rounded edges for the purpose of making the frame light and strong.

Any suitable platen and means for supporting the same may be employed. As shown the platen 27 is of the usual form and is mounted at its ends to rotate in the frame 28 of a carriage 29. The carriage 29 moves along a normally fixed member, bed or support 30, and has a movable member 31 which is opposed to the fixed support or bed 30, and said members form race-ways in which are arranged balls 32 forming a bearing for the member 31 of the carriage. 90

Various means may be employed for feeding the carriage for letter-spacing and as the escapement mechanism therefor. As shown the carriage is provided with a rack-bar 33 which extends lengthwise of the carriage 95 and meshing with said rack-bar is a pinion 34, Fig. 1, and this pinion is held to rotate on a shaft 35 projecting under the carriage bed or support 30 to the lower end of which is held a ratchet wheel 36. This ratchet 100 wheel 36 forms a part of the escapement mechanism 37 and is located above the bracket or plate 38 in which one end of the shaft 35 is journaled, the ratchet wheel 36 being held to rotate with the shaft 35, and 105 adapted to engage the ratchet wheel is an escapement device or lever 39. This lever or device 39 comprises two parts or members 40 and 41, and carried by the member or part 41 are the pawls 42 and 43, Fig. 5, 110

the former of which is fixed and the latter loose, and said pawls are adapted to engage alternately the teeth of the ratchet wheel 36 to permit said ratchet wheel to rotate with a step-by-step movement. The carriage is moved in one direction by a spring, and the movement of the carriage transmits a rotary movement to the ratchet wheel 36 through the rack-bar 33 and pinion 34. The end of the member 40 of the lever 39 is in the path of a vertically movable bar 44, and this bar is operated by each of the key-levers, not shown, on their downward movement in any suitable way to release the escapement, this feature as well as the way the carriage is supported, elevated, and adapted to be folded over above the keyboard being of any desired construction.

The carriage may be locked at the end of a line and may be permitted to move several spaces for the addition of one or more letters at the end of a line if desired. A bar 45, Figs. 2 and 5, is pivoted at its ends in the carriage frame and is normally forced in one direction by a spring 46. This bar 45, Fig. 2, is provided with a plurality of slots forming a series of teeth, and engaging certain of these teeth is a pendant arm 47. This arm may be adjusted along the bar 45, and is provided with ribs 47^a on opposite sides of its outer part adapted to fit between the teeth of the bar, and with a part 47^b that spans the opposite side of the bar to detachably clamp the arm thereto. As the carriage travels forward the pendant arm 47 is adapted to engage the end 48, Figs. 4 and 5, of a lever 49. This lever 49 is pivoted at 49^a to the carriage bed and is normally forced in one direction by a spring 50, Figs. 2 and 4, and the end 51 of said lever is provided with an outwardly-projecting pivoted member 52, and is made curved so as to extend adjacent to the end 53 of the arm 40 of the escapement lever 39. When the pendant arm 47 engages the end 48 of the lever 49, it will force the member 52 of the lever 49 over the end 53 of the member 40 of the lever 39, thus preventing the vertically moving escapement releasing bar 44 from operating said escapement lever arm 40. As the lever arm or member 40 cannot be operated in this position by any of the keys, the ratchet wheel cannot move, and this results in holding and locking the carriage against movement until the lever 49 is released. The lever 49 has a second projecting portion 54 to provide a space between the part 54 and the end 48 so that when the pendant arm 47 is released therefrom the carriage may be moved a distance according to the length of the space between the ends or engaging parts 48 and 54 for the addition of letters at the end of the line and will then be again locked by the arm 47 engaging the end 54 to force the lever 49 to a position to

lock the escapement lever 39 against movement. The bar 45 has a lever 55 held thereto, Figs. 2 and 6, and this lever is provided with a finger portion 56 by which the said bar may be quickly and conveniently moved on its pivot and the arm 47 released from engagement with the lever 49.

While I show certain features of a typewriting machine other than the present invention, as for example the escapement mechanism, this and other features not forming a part of the present invention, are claimed in separate and independent applications filed by me.

Having thus described my invention, I claim as new and desire to secure by Letters Patent:

1. In a typewriting machine, the combination of a support, a carriage adapted to travel along said support, an escapement mechanism having a lever carrying the escapement dogs, a bar having a relative rocking movement only mounted on said carriage, a device adjustably held to said bar and pendent therefrom, a lever pivotally held to the support and having one end provided with two spaced engaging parts arranged in the path of movement of said device and having its other end adapted to be moved into the path of movement of the dog-carrying lever of the escapement mechanism and adapted to directly engage said latter lever and hold the same against movement when either of said engaging parts are engaged by said device, and means for releasing the device from engagement with the lever whereby the escapement mechanism may be locked at two distinct points.

2. In a typewriting machine, the combination of a support, a carriage adapted to travel along said support, an escapement mechanism having a lever carrying the escapement dogs, a horizontally arranged bar having a rocking movement and mounted on said carriage, a device held to said bar and pendent therefrom, a horizontally arranged lever pivotally held to the support and having one end provided with a plurality of engaging parts arranged in the path of movement of said device and having its other end adapted to be moved into the path of movement of the dog-carrying lever of the escapement mechanism and adapted to directly engage said latter lever and hold the same against movement when said engaging parts are engaged by said device, and means for releasing the device from engagement with the lever whereby the escapement mechanism may be locked at distinct points.

3. In a typewriting machine, the combination of a support, a carriage adapted to travel along said support, an escapement mechanism having a lever carrying the escapement dogs, a bar having a rocking movement and mounted on said carriage, a device

- held to said bar and pendent therefrom, a lever pivotally held to the support and having one end provided with spaced engaging parts arranged in the path of movement of said device and having its other end adapted to be moved into the path of movement of the dog-carrying lever of the escapement mechanism and adapted to directly engage said latter lever and hold the same against movement when said engaging parts are engaged by said device, and a finger lever for rocking the bar and releasing the device from engagement with the lever to lock the escapement mechanism at distinct points.
4. In a typewriting machine, the combination of a support, a carriage adapted to travel along said support, an escapement mechanism having a lever, a horizontally arranged bar having a relative rocking movement and mounted on said carriage, a device held to said bar and pendent therefrom, a spring tending normally to rock the bar in one direction, a finger lever for rocking the bar in the opposite direction, and a lever pivotally held to the support and having one end adapted to be engaged by said device and having its other end adapted to be moved into the path of movement of the escapement lever and adapted to engage directly said latter lever and hold the same against movement.
5. In a typewriting machine, the combination of a support, a carriage adapted to travel along said support, an escapement mechanism having a lever, a horizontally arranged toothed bar mounted on said carriage, a device adjustably held to said bar and pendent therefrom, and a lever pivotally held to the support and having one end arranged in the path of movement of said device and having its other end adapted to be moved into the path of movement of the escapement lever and to directly engage said latter lever and hold the same against movement.
6. In a typewriting machine, the combination of a movable carriage, a support therefor, a platen supported on the carriage, an escapement mechanism having a lever, a horizontally arranged and pivotally held locking lever adapted to move into the path of a part of the escapement lever and prevent the carriage from moving, a spring normally forcing the locking lever in one direction, said lever having two spaced projecting portions, and a pendent and rocking device movable with the carriage and adapted to engage the projecting portions of the lever in succession and to be released therefrom to permit further movement of the carriage and then automatically stop the carriage again.
7. In a typewriting machine, the combination of a traveling and rocking bar, a device held to said bar, a horizontally pivoted lever adapted to be engaged by said device, and an escapement mechanism having a lever adapted to be directly engaged and locked against movement by said first-mentioned lever.
8. In a typewriting machine, the combination of a carriage, a device movable with the carriage, a lever adapted to be engaged by said device, and an escapement mechanism having a lever adapted to be directly engaged by and locked against movement by said first-mentioned lever at two distinct points.
9. In a typewriting machine, the combination of a carriage bed, a carriage movable along said bed, a bar pivotally held to the carriage and traveling therewith, a device held to said bar, a horizontally pivoted lever located under the carriage bed and having parts thereof adapted to be engaged directly by said device, and an escapement mechanism having a lever located adjacent to the first-mentioned lever and adapted to be directly engaged and locked against movement by said first-mentioned lever.
10. In a typewriting machine, the combination with a movable carriage, of a support therefor, a platen supported on the carriage, an escapement mechanism, a pivotally held lever adapted to move in the path of a part of the escapement mechanism to prevent the carriage from moving, a bar mounted on the carriage and having a rocking movement only, and a device held to said bar and movable with the carriage and adapted to engage the lever to force the same to lock the escapement mechanism.
11. In a typewriting machine, the combination with a movable carriage, of a support therefor, an escapement mechanism, a horizontally arranged and pivotally held lever adapted to move in the path of a part of the escapement mechanism to prevent the carriage from moving, and a device mounted on the carriage and having a relative rocking movement only and adapted to engage the lever to force the same to lock the escapement mechanism.
12. In a typewriting machine, the combination with a support, of a carriage adapted to move along the support, a bar supported by the carriage and having a rocking movement only thereon, a device carried by the bar, escapement mechanism, a lever provided with two projecting parts spaced apart and adapted to be engaged by the device mounted on said bar and having its other end provided with a pivotal member adapted to engage with a part of the escapement mechanism to lock the same against movement, and a spring for forcing the lever out of engagement with the escapement mechanism.
13. In a typewriting machine, the combination with a support, of a carriage adapted to move along the support, a bar

4
supported by the carriage, a device carried by the bar, escapement mechanism, a lever provided with two projecting parts spaced apart and adapted to be engaged by the device in succession and having its other end provided with a pivotal member adapted to engage with a part of the escapement mechanism to lock the same against movement, and a spring for forcing the lever 10 out of engagement with the escapement mechanism.

14. In a typewriting machine, the combination with a support, of a carriage adapted to move along the support, a bar supported by the carriage and having a 15 rocking movement only, a device carried by

the bar, escapement mechanism, a horizontally arranged and pivoted lever provided with two projecting parts spaced apart and adapted to be engaged by the device in succession to engage with a part of the escapement mechanism to lock the same against movement, and a spring for forcing the lever out of engagement with the escapement mechanism. 20
